UNITED STATES PATENT OFFICE.

ELLIS J. WOOLF AND JAY F. WOOLF, OF MINNEAPOLIS, MINNESOTA, ASSIGNEES TO THE WOOLF CYCLE MOTOR COMPANY, OF MINNEAPOLIS, MINNESOTA, A CORPORATION OF ARIZONA.

GAS ENGINE.

Application filed May 24, 1920. Serial No. 383,733.

To all whom it may concern:

Be it known that we, ELLIS J. WOOLF and JAY F. WOOLF, citizens of the United States, residing at Minneapolis, in the county of Hennepin and State of Minnesota, have invented certain new and useful Improvements in Gas Engines, of which the following is a specification.

Our invention relates to gas engines of the two-cycle type and has for its object to provide improved means of carbureting and controlling the charging fluid and of cooling the cylinder without the use of water or other circulating medium.

The full objects and advantages of our invention will appear in connection with the detailed description thereof and are particularly pointed out in the claims.

In the drawings illustrating an application of our invention in one form,—

Fig. 1 is a sectional elevation view taken through the motor including a pair of cylinders on the line 1—1 of Fig. 2. Fig. 2 is a sectional plan view taken on line 2—2 of Fig. 1. Fig. 3 is a sectional elevation view on line 3—3 of Fig. 2. Fig. 4 is a sectional plan view on line 4—4 of Fig. 1. Fig. 5 is an enlarged sectional elevation view taken on line 5—5 of Fig. 2.

Our invention is shown applied to a double-unit engine, that is a unit including two cylinders, in which application it is most efficient, but the principles of the invention may be applied efficiently to one or any desired number of cylinders. As shown, explosion cylinders 10, 11 are closed at their top by plugs 13 embodying the usual spark plug. Cylindrical casings 14, 15 surround the lower part of the cylinders 10 and 11 and extend a considerable distance below, the lower open end of cylinders 10 and 11 opening directly into the interior of cylinders 14 and 15. Within cylinders 10 and 11 operate the main pistons 16, 17 which are formed integral with enlarged pistons 18, 19 operating within the cylinders 14, 15. The crankshaft 20 is journaled in a multiplicity of bearings formed in conjunction with the walls of cylinders 14, 15 extending across an eccentric chamber 21. The crankshaft has in eccentric chamber 21 an eccentric 22 which communicates by a compound rod 23, 24 with a pair of tubular valve members 25, 26 integrally connected and movable

as a unit and operating in a cylindrical valve chamber 27 formed between the cylinders 14 and 15. The upper end of valve chamber 27 leads directly into an exhaust pipe 28 as shown in Figs. 1 and 5 and this exhaust pipe is surrounded by a casing 29 forming an annular chamber 30. Air passageways 31 and 32 are formed by casing extensions as indicated in Fig. 3. Passage 31 communicates with the outside air through ports 34 and 35, while similar ports 36 and 37 lead to passageway 32, the latter ports preferably being partially closed by plugs 38. Air from passageway 31 passes through a passage 39 into the space 30 surrounding the exhaust tube 28, from which it goes by a passageway 40 into the passage 41 from the passageways 32. Passageway 41 communicates through a port 42 with the primary inlet of carburetor mechanism 43 secured upon the engine casing immediately back of the valve chamber 27. This air then passes through a port 44 past the needle valve 45 for supplying fuel from feed 46, thence through a reversely-curved passage 47 and a second passage 48 directly to the interior of valve chamber 27 below the valve member 25. This primary air will therefore be considerably heated by passage along and around the exhaust pipe 28.

The inlet and exhaust of the engine both pass through similar passageways into the valve chamber 27. These passageways are well illustrated in Figs. 1, 2 and 3 wherein a multiplicity of exhaust ports 50 (in the example shown being four in number) communicate with passages 51, 52 which open into the valve chamber 27 and exhaust directly through the same into exhaust pipe 28, the exhaust from the two cylinders 10 and 11 being regulated or controlled by the upper portion of valve 25.

It will thus be seen that not only is the primary air going to the carburetor heated by passage over and around the exhaust pipe 28, but also by passage along walls 53 separating exhaust passages 52 from passages 31 and 32. Ports 54 positioned below ports 51 lead from cylinders 10 and 11 through passageways 55 into chambered passageways 56 at the sides of the cylinders 14 and 15, said chambered passageways being formed by casing members 57, 58 formed in conjunction with base members 59 so that

the passages 56 are in communication with the main crank chamber 60 as best shown in Fig. 3. The fuel mixture from pipe 48 enters valve chamber 27 between the upper and lower valve members 25 and 26 and passes through ports 61 and passageways 62 (indicated in dotted lines in Fig. 3) into chambers 56 at a point somewhat below the passageways 55 by which such fuel mixture is 10 ultimately introduced into cylinders 10 and 11.

Adjacent to carburetor passageway 43 for primary air is a secondary air passageway 63 which communicates by passage 64 with 15 the eccentric chamber 21, which eccentric chamber, as heretofore noted, is in direct communication with the lower part of the valve chamber 27. The lower valve member 26 is, as shown, provided with staggered 20 half-cylindrical portions alternately registering with ports 65 and 66 entering the interior of cylinders 14 and 15 below piston members 18 and 19, by which means the secondary air is sucked into the said cylinders 25 and into the crank chambers 60 from whence it is forced into the chambers 56 back of the fuel charge entering said chambers from passageways 62. The outstroke of pistons 18 or 19 will thus have the effect of forcing 30 the unheated cold air which has passed into the cylinder chamber 14 or 15 and crank chamber 60, through the chambers 56, and into cylinders 10 and 11 through ports 54 shortly after ports 50 are uncovered for exhaust. The result is that there is driven 35 into the explosion cylinder after exhaust a stratified charge of scavenging air trapped in chambers 56 and passageways 55 above the charge coming through passageways 63, 40 then the fuel charge and finally additional air to mix therewith and form perfect combustion, insuring complete injection of the fuel charge without waste or without loss through exhaust ports, and leaving a fresh 45 charge of cold air in the upper portion of chambers 56 and in passages 55 for the succeeding cycle.

The pump members 18, 19 also operate to force a large stream of atmospheric air 50 along the walls of cylinders 10 and 11 and around exhaust passages 51, 52 in suchwise as to effect cooling without the use of any water circulation. The construction for effecting this is best shown in Figs. 3 and 55 4. Surrounding the upper portion of cylinders 10 and 11 and positioned in annular relation thereto is a cylinder hood 70 which is connected by a multiplicity of radial pin members 71 cast integrally between cylinder 60 10 and cylinder 70. The cylinders 10 (or 11) and 70 form an annular chamber bridged by numerous pins 71 and which chamber has an annular passageway 73 opening into an annular chamber 74 surrounding cylinder 65 10 immediately above the exhaust pas-

sageways 51. As shown in Fig. 2, the chamber or passageway 74 communicates by vertical passageways 75, 76, 77 and 78, going by the exhaust passage 51 to a second annular chamber 79 wherein is an annular flange 80 70 for constraining the air to move along the lower walls of exhaust passages 51 and against the lower portion of walls of cylinder 10 (or 11). From chamber 79 the air passes around the inlet passages 55 into an 75 annular chamber 81 below the same in direct communication with the chamber formed by cylinders 14 or 15 above pistons 18 or 19. Surrounding the cylinder 70 is a cylindrical hood 82 which forms an annular 80 chambered passageway 83 open to atmosphere at the lower part, as indicated at 84, and communicating through an annular opening 85 with the upper part of the chamber formed between cylinders 10 and 70. 85

It will be apparent from the above description that as piston 18 (or 19) moves back and forth it will alternately draw and force out a large volume of air through the series of passageways 83, 73, 74, 79, 81. This 90 air will, therefore, travel in immediate proximity and in contact with outer walls of cylinder 10 or 11, the outer walls of exhaust passageways 51, around the heat-withdrawing pins 71 and along both walls of the 95 cylinder 70 communicating through the pins 71 with the main walls of cylinder 10.

The result is that the explosion cylinder and the exhaust passageways are maintained at a sufficiently reduced temperature to operate without the use of any cooling medium other than the air pumped in and out by the action of the upper portion of piston 18 or 19. At the same time the pistons 18 (or 19), in cooperation with the valve members 105 25 and 26 and the double-passaged carburetor mechanism 43, 63 are operating to draw charges of explosive mixture and of atmospheric air and to cause said charges to be delivered into the chambers 56 in stratified 110 relation and thereafter to be forced into the explosion cylinder whereby scavenging air first enters, followed by the fuel charge and in turn followed by atmospheric air back of the fuel. 115

During the downward or working stroke of the pistons, the sleeve valves close the charging ports, and the large ends of the pistons close the free air ports and pre-compression begins in the crank chamber. 120 This pre-compression continues until the sleeve valves first uncover the outer exhaust ports and the piston heads next uncover the inner exhaust ports and exhaust the combustion cylinders down to less than charging 125 pressure and finally uncover the charging ports when the pre-compressed mixture enters the combustion cylinders, the scavenging air first sweeping the piston heads and meeting at a common center in equal vol- 130

umes and under equal pressures is deflected upward through the central zone of the combustion cylinders to the centrally located spark plugs and is deflected around and over the wall of the compression space, then downward over the cylinder walls toward the exhaust ports. As the sleeve valve closes the exhaust ports before the piston head closes the charging ports, the fresh charge will not reach the exhaust ports, and the products of the previous combustion not expelled by the incoming charge will be left immediately surrounding the closed exhaust ports while the free air following the gas charge into the cylinders is left immediately over the piston heads, thus stratifying the gas and air in the combustion cylinders.

The result is a self-contained air-cooled two-cycle motor wherein a single valve controls the operation of two units and all parts are operated directly from the crankshaft and in conjunction with the engine piston.

We claim:

1. A two-cycle engine comprising a cylinder casing having a series of annular inlet ports, a casing surrounding said cylinder and providing chambered passageways in communication with said ports, a crank-case chamber in communication with said chambered passageways, a valve chamber, means for admitting fuel mixture into one part of said valve chamber and for admitting atmospheric air into another part of said valve chamber, means for admitting said fuel mixture from the valve chamber into said chambered passageways, means for admitting the air from said valve chamber into the crank-case chamber, and a valve member movable as a unit in said chamber for controlling the admission of said fuel gas and air.

2. A two-cycle engine comprising a cylinder casing and inlet ports thereto, a second casing forming a chambered passageway a crank casing in communication with said passageway, means for admitting fuel mixture into the chambered passageway, means for admitting atmospheric air into the crank-case chamber, and a valve member movable as a unit and operated in timed relation to the movement of the engine piston for controlling the admission of said fuel gas and air.

3. A two-cycle engine comprising a cylinder casing and inlet ports thereto, a second casing forming a chambered passageway a crank casing in communication with said passageway, means for admitting fuel mixture into the chambered passageway, means for admitting atmospheric air into the crank-case chamber, and a valve member comprising a pair of integrally-connected portions movable as a unit in timed relation to the movement of the engine piston, one of said portions controlling admission of fuel

mixture to the chambered passageway and the other portion controlling admission of air to the crank-case chamber.

4. A two-cycle engine comprising a cylinder casing having inlet ports, a casing formed in conjunction therewith and providing a chambered passageway in communication with said ports, a crank-case chamber in communication with said chambered passageways, a valve chamber, means for admitting fuel mixture into one part of said valve chamber and for admitting atmospheric air into another part of said valve chamber, means for admitting said fuel mixture from the valve chamber into the chambered passageway, means for admitting air from said valve chamber into the crank-case chamber, and a valve member movable as a unit in said chamber for controlling the admission of said fuel gas and air.

5. A two-cycle engine comprising a cylinder casing having inlet ports, a casing formed in conjunction therewith and providing a chambered passageway in communication with said ports, a crank-case chamber in communication with said chambered passageways, a valve chamber, means for admitting fuel mixture into one part of said valve chamber and for admitting atmospheric air into another part of said valve chamber, means for admitting said fuel mixture from the valve chamber into the chambered passageway, means for admitting air from said valve chamber into the crank-case chamber, and a valve member comprising two integrally-connected portions movable as a unit in said chamber, one portion controlling admission of the fuel gas and the other portion controlling the admission of the air.

6. A two-cycle engine comprising a cylinder casing having inlet ports, a casing formed in conjunction therewith and providing a chambered passageway in communication with said ports, a crank-case chamber in communication with said chambered passageways, a valve chamber, means for admitting fuel mixture into one part of said valve chamber and for admitting atmospheric air into another part of said valve chamber, means for admitting said fuel mixture from the valve chamber into the chambered passageway, means for admitting air from said valve chamber into the crank-case chamber, and a reciprocating double-sleeve valve integrally connected and movable as a unit in said valve chamber, one of said sleeves controlling admission of fuel gas and the other sleeve controlling admission of air.

7. A two-cycle engine comprising a casing forming an explosion cylinder, a chambered passageway in communication therewith, a crank-case chamber in communication with the chambered passageway, a valve chamber

- 4
- having means of separate communication to the chambered passageway and the crank-case chamber, an eccentric chamber formed in communication with the valve chamber, 5 means for admitting air to the eccentric chamber and lower portion of the valve chamber, means for admitting fuel mixture to the valve chamber at a higher point therein, a piston operative in the explosion cylinder, a crank-shaft connected with said piston and extending across the eccentric chamber, a reciprocating valve member in the valve chamber, and an eccentric on said crank-shaft in the eccentric chamber for operating said valve in timed relation to the operation of the piston to control admission of air to the crank-case chamber and admission of fuel mixture to the chambered passageway.
- 10 8. A two-cycle engine comprising a pair of explosion cylinders and their crank-case chambers and an intermediate cylindrical valve chamber, a valve member therein comprising a pair of integrally-connected sleeve parts dividing the valve chamber into two separated portions, means for admitting fuel mixture into one of said portions, means for conducting it therefrom into each of said explosion cylinders, means for admitting atmospheric air into the other portion of the valve chamber and for conducting it therefrom into each of the crank chambers, and means to move the valve member in timed relation to the pistons of the engine for controlling the passage of said fuel gas and air alternately to the explosion cylinders and crank chambers respectively.
- 15 9. A two-cycle engine comprising an explosion cylinder and its crank-case chamber and a valve chamber adjacent thereto, a valve member therein comprising a pair of integrally-connected sleeve parts dividing the valve chamber into two separated portions means for admitting fuel mixture into one of said portions, means for conducting it therefrom into said explosion cylinder, means for admitting atmospheric air into the other portion of the valve chamber and for conducting it therefrom into the crank chamber, and means to move the valve member in timed relation to the piston of the engine for controlling the passage of said fuel gas and air to the explosion cylinder and crank chamber respectively.
- 20 10. A two-cycle engine comprising a casing forming an explosion cylinder and its crank-case chamber and a valve chamber adjacent thereto, a valve member therein comprising a pair of integrally-connected piston sleeves dividing the chamber into three separated portions, means for permitting exhaust from the explosion cylinder through the upper portion, means for admitting fuel mixture into the middle portion, means for conducting it therefrom into
- 25 said explosion cylinder, means for admitting atmospheric air into the lower portion of the valve chamber and for conducting it therefrom into the crank chamber, and means to move the valve member in timed relation to the piston of the engine for controlling the exhaust through said upper portion of the valve chamber and the passage of said fuel gas and air to the explosion chamber and crank chamber respectively.
- 30 11. A two-cycle engine comprising a pair of explosion cylinders and their crank-case chambers and an intermediate cylindrical valve chamber opening at its upper end into the exhaust pipe, a valve member in the chamber comprising a pair of integrally-connected piston sleeves dividing the valve chamber into three separated portions, means for permitting admission of gases of combustion from both cylinders through the upper portion of said valve chamber, means for admitting fuel mixture into the middle portion, means for conducting it therefrom into each of said explosion cylinders, means for admitting atmospheric air into the bottom portion of the valve chamber and for conducting it therefrom into each of the crank chambers, and means to move the valve member in timed relation to the pistons of the engine for controlling the exhaust from each explosion cylinder, and the passage of said fuel gas and air alternately to the explosion cylinders and crank chambers respectively.
- 35 12. A two-cycle engine comprising a casing forming an explosion cylinder, a second casing forming a second cylinder and an annular space surrounding the explosion cylinder and open to atmosphere, a piston in the explosion cylinder, a second piston connected therewith and operative in the second cylinder for pumping atmospheric air back and forth through said space over the walls of said explosion cylinder; and a hood enveloping the portion of said casing forming the annular space and providing a second annular space about said portion whereby the air pumped back and forth will be forced to travel along both sides of said portion.
- 40 13. A two-cycle engine comprising a casing forming an explosion cylinder and a multiplicity of exhaust and inlet passages connected therewith and also forming a valve chamber and a single exhaust passage connected with said multiplicity of exhaust passages and with the valve chamber, and a chambered passage connected with said multiplicity of inlet passages and with the valve chamber, an exhaust pipe having connection with the valve chamber, said casing also forming air passages extending along said single exhaust pipe and around the exhaust pipe and leading from thence to the
- 45 50 55 60 65 70 75 80 85 90 95 100 105 110 115 120 125 130

valve chamber at a point separated from the entrance of the exhaust pipe into said valve chamber, a fuel feed nozzle projected into said last-named passageway, and a valve 5 member movable as a unit in the valve chamber for controlling the exhaust gases therethrough and to the exhaust pipe and

for controlling the admission of fuel mixture from the valve chamber to the inlet passages.

In testimony whereof we hereunto affix our signatures.

ELLIS J. WOOLF.
